Philip S. Hall
ATTORNEY

UNITED STATES PATENT OFFICE.

LESLIE S. HALL, OF ERIE, PENNSYLVANIA, ASSIGNOR TO WILLIAMS TOOL CORPORATION, OF ERIE, PENNSYLVANIA.

DIE HEAD FOR THREADING MACHINES AND THE LIKE.

Application filed March 25, 1925. Serial No. 18,250.

My invention relates to machinery and primarily to that type known as a pipe or bolt threading machine.

The primary object of my invention is to provide a simplified die head for a machine of this character including a novel means for setting the dies or thread cutting tools in various positions for threading pipe of different sizes.

10 Another object is to provide a simple and effective means for locking the dies in their set or adjusted position.

Another object contemplates the provision of means for locking the dies as a part of 15 the setting unit.

A still further object is to place the die operating and locking unit in such position as to enable the operator to readily manipulate the various parts easily and quickly.

20 Other objects and advantages in details of construction and operation will be apparent as the description proceeds, reference being had to the accompanying drawings wherein like reference numerals indicate like 25 parts.

In the drawing:

Figure 1 is a side view of my improved die head.

Figure 2 is a front view thereof, certain 30 parts being removed for clearness of illustration.

Figure 3 is a detail side view, partly in section, showing the operation of the die setting means.

35 The carriage of my improved die head is indicated generally by the reference numeral 1 and is adapted to slide on ways of the machine (not shown) to which it is applied. The carriage 1 is provided with a rigid upstanding supporting member 2, provided on its front face with a protruding bearing surface 3, for rotatably supporting an operating ring 4, hereinafter called the cam ring. A cover plate 5 is mounted by 40 bolts 6 to the supporting structure 2 and retains the cam ring 4 in proper position on its bearing.

45 As will be noted from Figure 2, the cam ring is cut away at various points as at 7, to reduce the weight of the same. The cam ring 4 is also provided on its face with eccentric cam ridges 8, adapted to engage in notches 9, in one of the sides of the chasers or thread cutting dies 10. The chasers 10 are mounted for sliding movement into and

out of work engaging position, that is, to and away from the opening 11 in the head, thru which the pipe or other work to be threaded projects, by means of slots or recesses provided in the projecting member 3 of the support 2. It will be understood therefore that rotation of the cam ring 4 will result in such sliding movement by the chasers 10, due to the ridge and notch connection 8 and 9.

60 The cam ring 4 is provided with an elongated bearing 13 secured thereto as by bolt 14, through which extends a screw shaft 15 provided at its outer end with a handle or turning piece 16. The lower end 17 of the 70 shaft 15 is adapted to engage with the upper end of a loosely mounted pin 18, slideable in a bushing 19, carried by the cam ring 4. The lower end 20 of this pin 18 rests upon and engages with the bearing surface 3. It will be understood therefore that upon turning the hand member 16 to 75 push the shaft 15 downwardly, the pin 18 will be forced into engagement with the bearing surface 3, thereby tightly locking 80 the cam ring from further rotation. Conversely, when the screw shaft 15 is rotated in the opposite direction, the pressure on the pin 18 will be relieved and the cam ring 4 is freely rotatable on the bearing surface 85 3, whereby to adjust the position of the dies.

85 In order to prevent possible slipping of the cam ring 4 on its bearing surface, due to pressure of the work or threading operation, the section of the bearing surface 90 3 with which the lower end 20 of the pin 18 engages, has been formed slightly eccentric to the center as shown in Figure 2, at 21. Therefore, if there should be any tendency for the cam ring 4 to slip on its 95 bearing after being locked, the eccentric surface 21 of the bearing acting as a wedge, cooperates with the lower end 20 of the pin 18 to positively prevent such slipping.

100 It will be noticed that my improved operating means for the cam ring for setting the chasers, and the locking means therefor are combined in a single unit. The operator therefore need use but one hand for both of these operations. The hand wheel 16 turns 105 the screw 15 to unlock the pin 18 and, using the hand wheel 16 and the bearing 13 as a handle, rotation of the cam ring 4 in the desired direction to adjust the dies as it may be required, is possible without changing 110

position. Again turning the hand wheel 16 to the right, locks the cam in its adjusted position.

From the foregoing description it will be understood that I have provided a novel type of die head for threading machines, which is a distinct improvement over those heretofore used. Of course the form shown and described is the preferred embodiment only and is susceptible to various changes in details of construction and operation, without departing from the spirit and scope of the invention. I do not limit myself therefore to the form shown other than by the appended claims.

I claim:

1. In combination with a die head including a head stock and a rotatable cam ring

thereon, an upstanding bearing on said ring, a screw threaded shaft rotatable in said bearing and provided at its outer end with hand gripping means, and means at the lower end of said shaft for engaging a surface of said head stock, said surface being eccentric with the center of said stock. 25

2. In combination with a die head including a head stock and a rotatable cam ring thereon, an upstanding bearing on said ring, a screw threaded shaft rotatable in said bearing and provided at its outer end with hand gripping means and a loosely mounted pin in said ring engageable at one end with the lower end of said shaft, and at the opposite end with an eccentric surface of said head stock. 30

LESLIE S. HALL.
